UNITED STATES PATENT OFFICE.

JOHN JAMES CANNON, OF LEICESTER, ENGLAND.

STOP MOTION FOR YARN-WINDING MACHINES.

Application filed November 3, 1923, Serial No. 672,474, and in England November 15, 1922.

This invention relates to stop motions for 5 yarn winding machines and has for its object an improved stop motion for use on winding machines of the vertical spindle type wherein the yarn is drawn from a hank on a rotary carrier and wound upon a bobbin mounted on a vertical spindle to which rotation is imparted by friction means consisting of a disc on the spindle driven by a 10 wheel.

In such machines the face of the disc makes frictional contact with the periphery of the driving wheel, and the present invention concerns a stop motion of the kind 15 wherein mechanism influenced by the winding yarn is employed to separate the disc from the wheel for the purpose of stopping the rotation of the bobbin.

In a form of such stop motion already 20 known the disc is slidable on the bobbin spindle and is moved from engagement with the driving wheel, by a lever normally controlled by gravity or a spring but actuated by the winding yarn in the event of a drag 25 occurring in the latter. In this case the yarn acts directly upon the lever to move same and the lever acts directly upon the disc to raise it from the wheel.

According to the present invention— 30 which is mainly, though not exclusively, intended for use with fine and delicate yarns such for example as silk and artificial silk—the disengagement between the driven disc and driving wheel is effected by automatic 35 braking means which are put into operation by a lever or equivalent member acted upon by connections from a spring controlled arm or the like subject to the influence of the running yarn.

40 It is a feature of the invention that the automatic braking means when released, in addition to disengaging the driving means, operate to arrest rotation of the spindle and bobbin. By quickly bringing the bobbin to rest when a drag on the yarn occurs breakage of the latter is prevented.

45 It is also a feature of the invention that the spring controlled arm when moved by a drag on the yarn is brought under the influence of a spring which imparts to it the necessary further movement for operating the connections to release the automatic braking means. By this arrangement the 50 yarn is not called upon to operate said connections and is therefore relieved of undesirable strain,

In the event of a drag on the yarn occurring such as may be caused by a ravel or other obstruction in the hank, the spring controlled arm is moved by the abnormal 60 tension in the manner described. The invention also includes means to operate the aforesaid connections when a knot occurs in the yarn.

These means comprise a movable knot 65 plate or detector arranged in connection with the controlling means of the said arm whereby the latter will be moved when the knot plate is moved by the contact of a knot therewith.

70 A convenient form of the invention is illustrated in the accompanying drawings in which—

Figure 1 is a side elevation of part of a 75 yarn winding machine with the invention applied thereto the said invention being shown in its normal or operative position.

Figure 2 is a front elevation of Figure 1.

Figure 3 is a side elevation of the device comprising the invention showing said 80 device in its inoperative or stopped condition.

Figure 4 is a detail view of part of the swift arm showing the cam thereon and its associated parts in their stopped position.

Figure 5 is a detail view of the cam or 85 detent showing the means of adjustment therefor.

Figure 6 is a side view of the swift arm showing the knot-plate attached thereto, and

Figure 7 is a front view of Figure 6.

90 Figures 3-7 are drawn to a larger scale than the rest of the drawings and like parts are designated by the same reference characters.

According to the invention the driven 95 friction disc 1 slides on the bobbin spindle 2 by means of a slot 3 formed in the boss 4 of said disc, said slot operating on a pin 5 on the spindle. Pivoted on a fixed bracket 6 or other suitable part underneath the disc 100 100 is a detent 7 having a cam or rounded edge 8 adapted to engage with the underneath face of the disc when the detent moves to an upright position in which direction it is drawn by a spring 9. The detent is held in a set position clear of the disc and with its spring tensioned by a lever 10 having thereon a shoulder or tooth 11 which engages with a projection 12 on the side of the detent as shown in Figure 1. The lever may be 110 counterweighted or acted by a spring to cause the shoulder to engage the projection.

Arranged above the disc but normally clear of same when it occupies the operative (driven) position is a brake pad or block 13 of wood, fibre or like material, mounted on a fixed bracket 14. The arrangement is such that when by movement of the lever the detent is released, the latter is moved by its spring and brings its cam or rounded extremity into contact with the face of the disc thereby raising the latter from the driving wheel 15 and forcing it into contact with the brake pad or block. The detent is so arranged and its end is so shaped that upon contact of the said end with the disc, the rotation of the latter will assist the detent in its movement thereby tending to produce a wedging effect of the disc between the end of the detent on the one side and the brake pad on the other side as shown in Figure 3. This effect speedily arrests the rotation of the disc and the detent is held in the forward position by the spring to keep the disc clear of the driving wheel.

In order that the bobbin may be stopped by hand when required a second detent may be provided having a handle extending therefrom. The second detent is operated from the first detent by a lateral projection which passes behind the second detent. Alternatively the second detent may be dispensed with and a handle 16, pivotally mounted on the fixed bracket 6 on a stud or screw 17, is provided having a plate or catch 18 attached thereto which is arranged to operate on a cam or rounded projection 19 formed on the lever 10. When the lever is pushed away from the operator the catch 18 engages the rounded projection and rides over same, thus forcing the lever downwards until the tooth 10 thereon clears the projection on the detent, when the spring 9 operates the said detent as above described and as illustrated in Figure 3. Upon the reverse movement of the handle taking place the other end of the catch 18 engages the detent and pushes it back clear of the friction disc until the tooth on the lever 10 again engages the projection on the detent as shown in Figure 1 when the bobbin will again revolve.

The yarn 20 passes from the hank 21 round a guide 22 and then over another guide 23 carried by a pivoted arm 24. This arm has fast upon its axle 25 or some other convenient part thereof a nose or cam 26 upon which a spring blade 27 bears. The nose and spring blade are arranged so that when the yarn is running over the guide at normal tension the spring will support the arm (Figure 1) and allow a certain amount of resilient movement so that it acts as a take up to compensate for slight variations in the yarn tension. When however, owing to a drag on the yarn the tension of the latter is increased abnormally so as to move the arm beyond its predetermined limit, the said

movement brings the other side of the nose or cam onto the spring blade with the result that the latter acts to depress instead of support the arm (Figure 4) which thereupon by means of a connecting rod 28 moves the beforementioned lever to release the detent. The rod 28 is loosely attached to an arm 29 which latter is rigidly mounted on the axle 25, and it is permitted a certain amount of lost motion before moving the lever in order that the previously mentioned resilient movement of the arm can take place under normal running of the yarn without putting the automatic braking means into action. This lost motion is brought about by means of a collar 30 on the rod, which engages a further rod 31 attached to the lever 10, said collar being adjustable on the rod and fixed in any predetermined position as shown in Figure 1.

The detent 7 is preferably adjustable vertically to vary the pressure applied to the friction disc, and to this end it is mounted on an eccentric bush 32 (Figure 5) having a milled edge flange 33 for easy adjustment by hand.

The aforesaid spring blade 27 may have arranged in connection therewith a knot plate by which means the bobbin is stopped when a knot occurs in the yarn. A convenient form thereof is illustrated in Figures 6 and 7 wherein said spring blade, instead of being anchored at its lower end as before, is free, and so constructed to engage a cam 34 fast on an axle 35 upon which the knot plate—consisting of two fingers 36 and 37 arranged in close proximity to each other—is slidably mounted. The said axle is for a certain part of its length, of square section and the plates 36 and 37 are adapted to slide on said square portion in order to follow the yarn as it moves from side to side of the hank. Normally the cam 34 applies a tension to the blade spring, but upon a knot striking the knot plate, said plate is moved in the direction of the arrow α and thus turns the cam in the direction of the arrow γ , the blade spring then, by reason of the said tension, helping in this movement until the various parts take up the position shown by the dotted lines in Figure 6 when the arm 24 is released and falls thus operating the connections hereinbefore described to release the detent.

It should be noted that the knot detector device 36, 37 is additional to the arm 24, subjected to the influence of the running yarn, and is arranged in association with the spring blade 27 controlling said arm so that the same connections serve for acting upon the lever 10 no matter whether the arm is moved as the result of undue yarn tension thereon or as the result of the action of the knot detector upon the spring 27.

The tension of the blade spring may be

adjusted by means of a screw or stud 38 and a wing nut 39 shown in Figures 1 and 6.

The details of construction may be varied without departing from the scope of the invention.

What I claim then is:—

1. In a yarn winding machine of the type wherein a vertical bobbin spindle is rotated by the contact of a disc thereon with a driving wheel, a stop motion mechanism comprising braking means which operate automatically to disengage said disc from the wheel and arrest rotation of same to stop the bobbin, a lever to normally hold said braking means out of action, a member controlled by the yarn, and a connection between said member and lever whereby, upon abnormal yarn tension, the latter is actuated to allow the braking means to become operative, said means thereupon operating independently of the lever and yarn controlled member.

2. In a yarn winding machine of the type wherein, a vertical bobbin spindle is rotated by the contact of a disc thereon with a driving wheel, a stop motion mechanism comprising braking means for acting automatically upon said disc to disengage it from the driving wheel and arrest its rotation, means to hold said braking means in a normally inoperative position, devices subject to movement under the influence of the running yarn, and connections between said devices and the said holding means whereby the braking means are released for operation when abnormal conditions in the yarn occur.

3. In a yarn winding machine of the type wherein a vertical bobbin spindle is rotated by the contact of a disc thereon with a driving wheel, a stop motion mechanism comprising a brake pad, a pivoted detent to engage the said disc and move it from the driving wheel and into contact with said brake pad, a spring to operate said detent, means to hold the detent in an inoperative position, and yarn actuated connections to move said means to release the detent.

4. In a yarn winding machine of the type wherein a vertical bobbin spindle is rotated by the contact of a disc thereon with a driving wheel, a stop motion mechanism comprising a brake pad located on one side of said disc, a pivoted detent located on the other side of said disc, a spring to actuate said detent whereby it moves the disc from contact with the driving wheel into engagement with the brake pad to arrest rotation of the spindle, a lever to hold the detent in a set position clear of the disc, and yarn actuated connections to actuate said lever to release the detent.

5. In a yarn winding machine of the type wherein a vertical bobbin spindle is rotated by the contact of a disc thereon with a driving wheel, a stop motion mecha-

nism comprising automatically acting braking means for arresting rotation of the spindle, a lever normally controlling and adapted to allow said braking means to become operative, a spring controlled arm subject to the influence of the running yarn, and connections between said arm and lever whereby when said arm is moved by undue tension on the yarn the lever is actuated to allow the braking means to act.

6. In a yarn winding machine of the type wherein a vertical bobbin spindle is rotated by frictional driving means, a stop motion mechanism comprising automatically acting braking means adapted to arrest rotation of the spindle, a lever normally controlling and adapted to allow said braking means to become operative, an arm subject to the influence of the running yarn, a spring controlling said arm, and connections between said arm and the lever whereby when said arm is moved by undue tension on the yarn the spring imparts further movement thereto to operate the lever for allowing the braking means to act.

7. In a yarn winding machine of the type wherein a vertical bobbin spindle is rotated by frictional driving means, a stop motion mechanism comprising automatically acting braking means adapted to arrest rotation of the spindle, a lever normally controlling and adapted to allow the braking means to become operative, an arm subject to the influence of the running yarn, a spring controlling said arm, a movable knot detector controlling said spring, and connections between said arm and the lever whereby upon the arm being moved by undue tension on the yarn or as a result of loss of control by the spring due to the release of the latter by the knot detector, the lever will be actuated by the connections to allow the braking means to act.

8. In a yarn winding machine of the type wherein a vertical bobbin spindle is rotated by the contact of a disc thereon with a driving wheel, a stop motion mechanism comprising a stationary brake pad adjacent one side of the disc, a pivoted detent having a cam-shaped end adjacent the opposite side of said disc, a spring to move said detent so that the cam-shaped end thereof engages said disc and moves it from contact with the driving wheel and into engagement with the brake pad, a spring controlled lever to engage the detent and hold it in an inoperative position, a device subjected to the influence of the running yarn, and connections between said device and the lever.

9. In a yarn winding machine of the type wherein a vertical bobbin spindle is rotated by the contact of a disc thereon with a driving wheel, a stop motion mechanism comprising braking means operating automatically to arrest rotation of the spindle,

4
a lever to normally hold said braking means inoperative, yarn actuated connections to operate said lever whereupon the braking means become operative independently of the lever, and a hand lever to operate said lever for rendering the braking means operative independently of the yarn actuated connections.

10. In a yarn winding machine of the type wherein a vertical bobbin spindle is rotated by frictional driving means, a stop motion mechanism comprising braking means operating automatically to arrest rotation of the spindle, a lever to normally hold said braking means in an inoperative position, yarn actuated connections to actuate said lever to put said braking means into action, and a hand lever adapted when moved in one direction to actuate the lever to render the braking means operative and when moved in the opposite direction, to return said lever to the normal position.

11. In a yarn winding machine of the type wherein a vertical bobbin spindle is

rotated by the contact of a disc thereon with 25 a driving wheel, a stop motion mechanism comprising a fixed brake pad on one side of said disc, a pivoted cam detent on the other side of said disc, a spring to move said detent into contact with said disc 30 whereby it shifts the disc from contact with the driving wheel and into engagement with the brake pad to arrest rotation of the spindle, a lever to engage the detent and normally hold it out of action, a device subjected to the influence of the running yarn connections between said device and the lever for moving the latter to release the detent when abnormal yarn tension occurs, and a manually operable member movable 40 in one direction to disengage the lever from the detent and movable in another direction to return the detent to normal position and re-engage it with the lever.

In testimony whereof I affix my signature. 45

JOHN JAMES CANNON.
